UNITED STATES PATENT OFFICE.

EDWARD BELMONT AND WALTER RUSSELL, OF LEAVENWORTH, KANSAS.

COLLAR ATTACHMENT.

1,083,981.

Specification of Letters Patent.

Patented Jan. 13, 1914.

Application filed September 6, 1912. Serial No. 718,903.

To all whom it may concern:

Be it known that we, EDWARD BELMONT and WALTER RUSSELL, citizens of the United States, residing at Leavenworth, in the county of Leavenworth and State of Kansas, have invented a new and useful device for the purpose of preventing the necktie binding to the collar of the wearer, holding the necktie in proper alinement, and facilitating the adjustment thereof.

The object of our invention relates more specifically to a novel, useful but simple device, primarily adapted to be used in conjunction with the usual linen or composition collar at present in such general use as part of the wearing apparel or clothing of men. It is a well known inconvenience to all users of neckties in combination with such collars, that the necktie often "binds" or "sticks" between the two folds of the collar, this condition being brought about by reason of the necktie being irregularly located between the collar folds, and also, to the extended frictional surface between the necktie and the inner collar fold. In order to overcome this difficulty, we have invented a small but effective device, invisible when in use, which not only greatly reduces the friction between the necktie and collar by providing a roller for the necktie to travel over when the wearer is adjusting same preparatory to tying the bow or other ornamental substitute, but also holds the necktie in proper alinement between the collar folds, preventing it from twisting, from "falling down" or "working up" in the back, and retains the necktie between the collar folds when the collar is temporarily discarded by the wearer, the necktie being in the proper position for use, without any adjusting being necessary, when the wearer again desires to use his collar and necktie.

In the accompanying drawings, Figure 1 is a sectional view of a shirt and collar at the rear, the "attachment" being shown in closed or operative position; Fig. 2 shows part of a collar, rear view, with a portion of the outside fold cut away showing the relative position of the attachment to the collar, the attachment being shown in open position; Fig. 3 illustrates a side view of the opened attachment; Fig. 4 a sectional view, looking down, on the line 6—7 of Fig. 2; Fig. 5 is an enlarged end view of the roller. Similar figures refer to similar parts throughout the several views.

Referring to the drawings, 8 denotes the inside collar fold, 9 the outside collar fold, 10 the shirt band and 11 the shirt proper. A collar-button 12 fastens the shirt to the inside fold 8 of the collar in the usual manner, the "attachment" being simply fastened to the head of the collar-button as shown, although any particular snap or fastener may be used for this purpose.

The "attachment" consists more definitely of two stamped pieces of sheet metal, 13 and 14 preferably of nickel-plated spring-steel and hinged together at 15 as shown. The upper piece 13 has a countersunk hole 16 with radiating notches 17 punched therein for the purpose of being forced over the collar-button-head, being retained in the illustrated position through the medium of the spring sectors necessarily produced by means of the notches 17. Spring tensioned laps 18 project upwardly for the purpose of preventing the "attachment" from turning circumferentially with the collar button 12 as a center, the inside collar fold being tightly held between these laps and the piece 13. The lower part of the piece 13 constitutes a hinge portion, being hingedly attached, by means of a pin as shown, to the hinge portions at the upper end of the piece 14.

The piece 14 has a vertical notch 19 cut therein for the purpose of better accommodating a roller 20, this roller being supported between the upper lip 21 which is formed by that part of the metal from which the notch is formed being bent at approximately right angles to the piece 14, and the lower lip 22. This roller is fluted or notched for the better engagement of the necktie therewith when in operation and more particularly shown in Fig. 5. The piece 14 has a curved configuration, more particularly shown in Fig. 4, the concave side adjoining the collar button when in use, this form protecting the necktie from coming in contact with the collar-button and interfering with its proper adjustment.

In operative position the "attachment" is as shown in Fig. 1, 23 denoting the necktie and illustrating how it travels over the roller 20, naturally greatly minimizing friction for the purpose previously stated. It will also be noted that the lips 21 and 22 prevent the necktie from working up or down between the collar folds, or sliding off the collar entirely, the advantage of this feature being

that the bow is sure to remain intact to the satisfaction and convenience of the wearer.

In use, the device operates as follows: The collar being attached to the shirt by the collar button in the usual manner, the hole 16 of the attachment is forced over the collar button head, the attachment occupying the position shown in Fig. 2. The necktie 23 is then held against the piece 14 with the upper 10 edge adjoining the lip 22, the piece 14, with the necktie still in position, is then simply turned on its hinges so that it occupies a position between the collar folds 8 and 9, more clearly shown by Fig. 1. The necktie 15 is now in position to be adjusted very conveniently for the proper length in which to tie the bow to the satisfaction of the wearer and to his convenience in wearing.

Having described our invention, we claim:

20. 1. A collar attachment having positive

means for attachment to a collar button, said collar attachment consisting primarily of a lower and upper part pivoted to each other, the upper part consisting of a slotted plate with a fluted roller revolvably mounted 25 in the slot.

2. A collar attachment consisting of a lower and an upper part pivoted to each other, the upper part consisting of a slotted plate with neck-tie retaining arms at each 30 extremity of the slot and a fluted roller revolvably mounted between the neck-tie retaining arms.

In testimony whereof we affix our signatures in presence of two witnesses.

EDWARD BELMONT.
WALTER RUSSELL.
